UNITED STATES PATENT OFFICE.

GEORGE A. BERRY, OF EXCELSIOR SPRINGS, MISSOURI, ASSIGNOR OF ONE-THIRD TO
W. J. MARSH, OF ST. LOUIS, MISSOURI, AND ONE-THIRD TO BERNARD C. BAYNES,
OF EXCELSIOR SPRINGS, MISSOURI.

PRICE-TICKET HOLDER.

1,392,622.

Specification of Letters Patent.

Patented Oct. 4, 1921.

Application filed February 21, 1919. Serial No. 278,397.

To all whom it may concern:

Be it known that I, GEORGE A. BERRY, citizen of the United States, residing at Excelsior Springs, in the county of Clay and 5 State of Missouri, have invented certain new and useful Improvements in Price-Ticket Holders, of which the following is a specification.

This invention relates to an improved 10 price ticket holder particularly designed for use in dry goods stores, clothing stores, haberdasheries, drug stores, department stores, and the like, and has as its primary object to provide a device of this character so constructed that the holder may be easily and 15 quickly engaged with an article of merchandise for displaying a price ticket thereon.

The invention has as a further object to 20 provide a holder wherein a price ticket may be readily engaged with the holder to be firmly held thereon.

And the invention has as a still further object to provide a ticket holder constructed to 25 resiliently grip the price ticket and thus maintain the ticket in proper position upon the holder held against tilting within its supporting loop.

Other and incidental objects will appear 30 during the course of the detailed description of the invention. In the drawings, wherein I have illustrated the preferred embodiment of the invention, and wherein similar reference characters designate corresponding 35 parts throughout the several views:

Figure 1 is a perspective view of my improved holder, the price ticket shown being conventionally illustrated,

Fig. 2 is a plan view of the device more 40 particularly illustrating the manner in which the price ticket is gripped by the holder,

Fig. 3 is a view similar to Fig. 1 and showing 45 a slightly modified form of the invention;

Fig. 4 is a perspective view showing a further modification.

In its preferred embodiment, as shown in Figs. 1 and 2 of the drawings, the ticket 50 holder of the present invention is formed from a single length of suitable resilient wire. From this length of wire a pin shank or supporting shank 10 is formed, the wire being looped forwardly at the upper end of

the shank to provide a downwardly directed 55 arm 11 lying in front of the shank 10 in spaced relation thereto. At the lower end of the arm 11 the wire is again bent laterally to form a ticket holding loop 12, the free end portion of which normally tends to 60 assume a position lying in a plane with the arm 11. At the upper end of the free end portion of the loop the adjacent end portion of the wire is again bent laterally to form a longitudinally bowed gripping arm 13 65 extending in front of the arm 11 at substantially right angles thereto and intersected medially by said arm. Consequently, the free end portion of the loop 12 will resiliently hold this gripping arm 13 against the 70 arm 11 and, owing to the longitudinal curvature of the gripping arm, the ends of this arm will thus normally intersect the plane of the arm 11 at opposite sides thereof. Formed on the free end of the arm 13 is an 75 angular downwardly directed terminal 13^a. It is now to be observed that the arm 11 is, at a point slightly above the gripping arm 13, offset laterally so that the shank 10 is thus supported in a plane passing medially 80 through the ticket holding loop 12 at right angles thereto. Formed as thus described, it will be seen that the holder may be readily produced. In use, a price ticket may be fitted within the ticket holding loop 12, a 85 ticket being conventionally shown at 14 in the drawings, when the shank 10 may be engaged, as will be readily understood, with an article of merchandise for connecting the holder therewith to display the ticket. In 90 this connection attention is particularly directed to the manner in which the ticket is held by the device. As shown in the drawings, the ticket is rested against the bottom portion of the loop 12 and is resiliently 95 gripped by the arm 13 acting to bind the ticket between this arm and the arm 11. The arm 13, being longitudinally curved will, as shown in Fig. 2, thus bow the ticket 100 longitudinally over the arm 11 so that the ticket will accordingly coact with the arm 11 and with the gripping arm to be firmly held against tilting within the supporting loop. However, as will be clear, the ticket may be readily displaced from the holder by 105 simply pulling upwardly thereon to disengage the ticket from within said loop. The terminal 13^a will, of course, assist in grip-

ping the ticket and will prevent marring thereof by the free end of the arm when the ticket is engaged with or removed from the holder.

5 In Fig. 3 of the drawings, I have illustrated a slight modification of the invention. In this modification a shank 10' is employed. This shank corresponds to the shank 10 of the preferred construction but is elongated. 10 Connected with said shank is an arm 11' corresponding to the arm 11 of the preferred construction. However, the arm 11' is straight while the shank 10' normally inclines toward the arm so as to resiliently 15 grip a thickness of fabric between the arm and shank when the shank is embedded in the fabric. At the lower end of the arm 11' is a ticket holding loop 12', the free end portion of which carries a laterally directed 20 gripping arm 13', these parts corresponding to the similar parts of the preferred construction and performing like functions.

In Fig. 4 of the drawings, I have shown a further modified form of the invention 25 wherein a shank 10^a is employed. This shank corresponds to the shank 10' of the prior modification but is somewhat longer and is connected to a base 15 so that the device may be used as a stand for supporting a 30 price ticket. Extending from the shank 10^a at its upper end is an arm 11^a. At the lower end of the arm 11^a is a ticket holding loop 12^a carrying at its free end a laterally directed gripping arm 13^a, this loop and arm 35 corresponding to the loop and arm of the prior modification.

In a further adaptation of the invention I employ a spring loop 20 which may be formed from a strip of suitable resilient sheet 40 metal and is rolled at its ends in order that

the loop may, as will be well understood, be readily engaged around the neck of a bottle. Gripped within one of the rolled portions at the ends of the loop is the shank 10' of the holder shown in Fig. 3, which will thus be 45 supported by the loop to upstand therefrom. Consequently, the loop may be engaged around the neck of a bottle, when a ticket may be fitted upon the holder to be supported thereby for display upon the 50 bottle.

Having thus described the invention, what is claimed as new is:

1. A ticket holder formed from a single strand of resilient wire and comprising a 55 shank, a bend at the upper end of the shank, an arm depending from said bend and having its lower end portion normally urged toward the shank, a lateral bend at the lower 60 end of said arm, a loop member rising from said bend, and a lateral gripping arm extending from the upper end of said loop member across the vertical plane of the shank and the first-mentioned arm.

2. A ticket holder formed from a single 65 strand of resilient wire and comprising a shank, a bend at the upper end of the shank, an arm depending from said bend and having its lower end portion normally urged toward the shank, a lateral bend at the lower 70 end of said arm, a loop member rising from said bend, a lateral gripping arm extending from the upper end of said loop member across the vertical plane of the shank and the first-mentioned arm, and a downwardly 75 directed terminal at the free end of said lateral gripping arm.

In testimony whereof I affix my signature.

GEORGE A. BERRY. [L.S.]
